UNITED STATES PATENT OFFICE.

HATTIE A. SMITH, OF WASHINGTON, DISTRICT OF COLUMBIA.

SKIRT-PROTECTOR.

1,197,240.

Specification of Letters Patent. Patented Sept. 5, 1916.

Application filed April 26, 1916. Serial No. 93,710.

To all whom it may concern:

Be it known that I, HATTIE A. SMITH, a citizen of the United States, residing at Washington, in the District of Columbia, 5 have invented a certain new and useful Improvement in Skirt-Protectors, of which the following is a specification.

This invention relates to skirt protectors and particularly to that class of protector 10 which is closed at the bottom so as completely to envelop the skirts of the wearer and protect them from splashing.

In devices of this character it is necessary so to support the bottom panel or closure of 15 the protector as to keep it clear of the ground. Two means toward this end have heretofore been used either singly or in combination. The first is to attach the panel to the legs of the wearer at or near the knees. 20 This draws the protector around the bottom edges of the wearer's skirts and up within the same and by interfering with the hang and free movement of the skirts greatly impedes the wearer. The second means is to 25 provide one or more straps or stays extending from or near the waist band of the protector to one or more points near the middle of the bottom panel. These straps necessarily are outside the wearer's skirts and by 30 interfering with and bunching the same impede the wearer and are uncomfortable. My invention avoids both these difficulties and provides a protector which hangs like an ordinary skirt and can hardly be distinguished therefrom when properly adjusted. 35 I accomplish this result by sustaining the central portion of the bottom panel on the skirt portion of the protector by inserting in it a plurality of spaced stiffeners extending 40 across the panel, and by sustaining the side portions of the panel by means of elastic anklets which are adjusted at or about the wearer's shoe tops. By properly proportioning the protector, the protected skirts 45 hang perfectly free. The spacing of the stiffeners allows the bottom panel to have a free and almost universal movement and the anklets by supporting the sides of the

bottom panel in a very slightly elevated position conceal the same and allow the sides 50 of the protector to hang freely and naturally, like a skirt.

Other and minor features of the invention will be made plain by the description of the preferred embodiment of the invention illustrated in the accompanying drawings, in 55 which:

Figure 1 is a perspective view showing the protector in use and illustrating the position assumed when the wearer is about to 60 mount a step; Fig. 2 is a fragmentary view illustrating the preferred form of waist band; Fig. 3 is a perspective view showing a portion of the bottom panel and one of the elastic anklets. In this view the protector 65 is turned inside out to show the preferred construction of the anklet and the method of attaching the stiffeners. Fig. 4 is a view looking at the outside of the bottom panel and showing the general proportions thereof; and Fig. 5 is a section on the line 5—5 of Fig. 4.

In the drawings 6 represents the skirt portion of the protector. The form of this is such as to conform to the skirts over 75 which it is to be worn, it being desirable that the protector hang freely and not confine the protected skirts unduly. The waist band 7 is of heavy elastic and the skirt portion 6 of the protector is laid in loose plaits 80 and tacked at intervals between the plaits to the waist band. This arrangement is preferred because the waist band is self adjusting and requires no placket or fastenings; but other known arrangements might 85 be used.

The bottom panel or closure 8 of the protector is preferably of the form shown in Fig. 4, though it may assume an oval or other form appropriate to the style of skirt 90 over which the protector is to be worn. The longer dimension of the panel is transverse to the protector. The form shown has been found by test to serve satisfactorily with skirts of somewhat varying styles and is 95 preferred because its straight form saves

material. The panel 8 is connected at its peripheral edge by a seam 9 to the skirt portion 6.

Extending across the panel 8 are a number of spaced parallel stiffeners 10, six being shown. These may be any of the usual types of dress stiffeners, such as "steels" or "bones" but I prefer a stiffener known by the trade name of "featherbone" because this has the right degree of elasticity and is light and non-corrosive. The stiffeners 10 extend the full width of panel 8 and are contained in pockets 11 stitched throughout their length to the panel 8. The stiffeners 15 thus extend across the panel 8 from the front to the back of the protector and support the panel at its middle portion directly from the skirt portion 6 of the protector.

Near each end of the panel 8 and consequently near the sides of the protector are the openings 12 large enough for the passage of the wearer's shoe. A cuff 13 made of a straight strip of material joined at its ends is fitted in each opening 12. One edge 20 only of the cuff is stitched smoothly to the edge of the opening 12. The other edge of the cuff is loosely gathered and tacked to the lower edge of an elastic band or anklet 14, so that the elastic and the gathered edge 25 of the cuff may be stretched to the size of the opening 12. If the elastic band 14 be of proper size for the wearer, the cuff 13 will lie almost flat in the plane of the bottom panel 8 when the protector is worn, the band 30 14 projecting upward therefrom. While not absolutely necessary it is desirable that the elastic anklet 14 be worn a little above the plane of the bottom panel 8 to support the latter at the extreme sides of the protector and to assist in rendering the bottom 35 panel invisible.

When the protector is properly proportioned to the skirts over which it is worn the latter hang perfectly free, as does the 40 skirt portion of the protector. The only impediment to movement is that offered by the panel 8 which is perfectly free to collapse upon itself and to swing or stretch in any direction. The panel 8 guides the 45 stiffeners 10 so that they do not interfere and the stiffeners support the panel in all positions assumed by the wearer.

Because of the loose use in this art of the words "stay" and "stiffener" to define the 50 same thing, I shall, in certain of the claims describe the stiffeners as "relatively rigid" in order to exclude such arrangements as extra plies of ordinary fabric which properly are stays only and have no intended 55 stiffening function. By describing the stiffeners as "relatively rigid" I do not, however, imply the exclusion of any of the known stiffening materials most of

which have an inherent resilient flexibility and all of which are characterized by 60 a definite stiffening function as contradistinguished from a mere staying or strengthening action.

The skirt protector finds its greatest utility as a rainproof overall, and for this purpose is preferably made of a waterproof fabric such as cravette cloth or the like. I do not, however, limit myself to any specific material.

While I have illustrated the best embodiment known to me, various modifications are 70 obviously possible, and fall within the scope of the invention.

Having thus described my invention, what I claim is:—

1. A skirt protector comprising in combination, a skirt portion; a panel mounted in the bottom of said skirt portion to close the same; and a relatively rigid stiffener extending across said panel to support the latter, said protector being provided with suitable leg openings.

2. A skirt protector comprising in combination, a skirt portion; a panel mounted in the bottom of said skirt portion to close the same; a plurality of spaced stiffeners extending across said panel to support the latter, said protector being provided with suitable leg openings.

3. A skirt protector comprising in combination, a skirt portion; a panel mounted in the bottom of said skirt portion to close the same, and provided with spaced leg openings; leg embracing cuffs in said openings for supporting adjacent portions of said 95 panel; and stiffeners extending across said panel between said openings for supporting the middle portion of said panel.

4. A skirt protector comprising in combination, a skirt portion; an oblong panel closing the bottom of said skirt portion and provided with leg openings adjacent its ends; elastic, leg-embracing cuffs in said openings; stiffeners extending transversely to said panel between said leg openings; and attaching means connecting said stiffeners with said panel throughout substantially the entire lengths of said stiffeners.

5. A skirt protector comprising in combination a skirt portion; an oblong panel closing the bottom of said skirt portion and provided with leg openings; cuffs mounted in said leg openings; elastic anklets each attached at one edge to the free edge of a cuff to contract the latter, said anklets when in use extending upward from said cuffs within the protector; and a plurality of stiffeners attached to said panel and extending across the same.

6. The combination with a skirt protector 125 including a skirt portion and a bottom clos-

ing panel provided with leg openings, of elastic anklets, one for each leg opening; and cuffs attached at one edge to the lower edge of a corresponding anklet and at the other edge to the edge of a corresponding opening, said cuffs being of such width as barely to permit the full contraction of the anklets without deformation of said openings, and said anklets, when in use, extending upward from said cuffs within the protector. 10

In testimony whereof I have signed my name to this specification.

HATTIE A. SMITH.
